CARTRIDGE ADAPTER FOR A FOUNTAIN PEN

Walter J. De Groft, Glen Ellyn, Ill., assignor, by mesne assignments, to Sanford Research Company, a corporation of Illinois

Filed July 13, 1961, Ser. No. 65,899

Term of patent 14 years

(Cl. D74—17)

The figure on the drawing is a perspective view of a cartridge adapter for a fountain pen showing my new design.

I claim:

The ornamental design for a cartridge adapter for a fountain pen, as shown.
